[57] CLAIM

The ornamental design for a pumpkin etcher, as shown and described.

DESCRIPTION

FIG. 1 is a front elevational view of a pumpkin etcher showing my new design, wherein the rear elevational view is a mirror image thereof;

FIG. 2 is a side elevational view, wherein the opposite side view is a mirror image thereof;

FIG. 3 is a top view; and,

FIG. 4 is a bottom view.
